UNITED STATES PATENT OFFICE.

MONROE E. MILLER, OF WASHINGTON, DISTRICT OF COLUMBIA, ASSIGNOR TO UNDERWOOD TYPEWRITER COMPANY, OF NEW YORK, N. Y., A CORPORATION OF DELAWARE.

VARIABLE ESCAPEMENT.

1,286,186.

Specification of Letters Patent. Patented Nov. 26, 1918.

Application filed February 3, 1916. Serial No. 75,972.

To all whom it may concern:

Be it known that I, MONROE E. MILLER, a citizen of the United States, residing at Washington, in the District of Columbia, 5 have invented new and useful Improvements in Variable Escapements, of which the following is a specification.

The present invention appertains to escapement mechanisms, and aims to provide a 10 novel and improved escapement mechanism for use upon typewriters especially, although it can be used in other kindred machines wherein a variable spacing escapement is desired.

15 With the ordinary typewriter, the spaces allotted the small and capital letters and other characters, such as the period, comma, semicolon, etc., are all the same, and it is the practice with this uniform spacing system, to provide type wherein many of the letters and other characters are made out of proportion. Thus, the letters i, j, etc., are widened, while the letters m and w are made narrower than ordinarily, as with printers' 20 type, so that these wide letters are crowded. Furthermore, the capital letters are only allowed the same spaces as the small letters, so that they are also out of proportion. It is thus necessary with prevailing typewriter 25 escapements to widen some of the characters unnecessarily, while others are made narrower, in order that the work will not have a broken appearance, but at the same time, the appearance of the work is marred, due 30 to the fact that some letters or characters are out of proportion.

It is the object of this invention to provide an escapement mechanism whereby the 35 various letters and other characters occupy spaces in proportion to their width, so that the narrow letters, periods, commas, etc., will occupy narrow spaces, while the wider letters and characters will occupy relatively wide spaces, thereby enabling harmonious and 40 properly proportioned type to be used. This escapement mechanism is so constructed and operable as to vary the steps made by the carriage when the various character keys are depressed.

45 Another object of the invention is the provision of an escapement mechanism so operable, that when the shift key or shifter

is depressed or otherwise operated for changing from small to capital letters, or the like, the capital letters will be given wider spaces 55 than the small letters, in order that the small and capital letters can be of proper proportions. For example, the small letters i, a and m are allotted spaces of increased widths in succession, while the capital letters I, A and 60 M are allotted spaces wider than the respective spaces allotted the small letters i, a and m.

A still further object of the invention is the provision of an escapement mechanism of the 65 character indicated, which will be operated after the character keys are depressed, and before the said keys are depressed sufficiently for completing the movement of the type against the platen, whereby there is no opportunity for blurring, since the carriage and its platen will have moved the proper amount before the type strikes the platen.

As a more specific object, the invention aims to provide an escapement wheel of 75 unique construction and carrying means co-operable with a pallet member or device for varying the steps or step movements by the wheel, said wheel being geared or otherwise connected to the carriage in a suitable manner, and being operated selectively by the character keys in order that the movement made by the wheel and carriage will be in proportion to the letter which is printed.

The invention has for another object, the 85 provision of a variable carriage feed escapement which is comparatively simple, compact and inexpensive in construction, which can be installed or used in present day typewriters without entailing prohibitive 90 trouble, alterations or expense, and which is feasible and practical.

The present mechanism also enables a typewriter to be built, to supplant the expensive linotype, monotype or similar machine, since newspaper columns and other printed matter can be typewritten, using an ordinary font of printers' type, and the matter typewritten can then be used as a basis for providing the plate or sheet of type 95 from which the newspapers or other matter is printed, the typewritten matter being readily transferred by any well known or special chemical process onto a lead or other 100

plate or sheet. This eliminates the setting or production of individual or lines of type, at a great saving. Furthermore, different typewriters having different styles and sizes 5 of type can be used with more convenience and less expense than the use of a number of linotype or similar machines.

With the foregoing and other objects in view which will be apparent as the nature 10 of the invention is better understood, the invention resides in the combination and arrangement of parts and in certain details, but it is to be understood that the disclosure is more or less typical, since changes 15 are possible, within the scope of what is hereinafter claimed, without departing from the spirit or principles of the invention, and which changes would be apparent to those skilled in the art in adapting the invention 20 to various typewriters.

The invention is illustrated in the accompanying drawings, wherein:—

Figure 1 is a front view of the escapement mechanism, portions being shown in the section on the line 1—1 of Fig. 3, and other parts also being shown in section, while some portions are broken away.

Fig. 2 is a plan view of the mechanism, portions being shown in section and others 30 being broken away.

Fig. 3 is a longitudinal section of the mechanism, portions being shown in section and others being broken away.

Fig. 4 is an enlarged sectional detail illustrating a portion of the escapement wheel and coöperating elements which act upon it.

Fig. 5 is a plan view of the key board, showing slight changes in the characters, the letters being the same as on a standard key 40 board typewriter.

Fig. 6 is a specimen of the work of an ordinary typewriter.

Fig. 7 is a specimen of the work when a typewriter embodying the present escapement is used, and showing the different 45 spaces allotted the various characters, whereby the printing is the same as that done by printers' type.

In the drawings, only those portions of 50 a typewriter are illustrated which coöperate directly with the present mechanism, to simplify the drawings, and to confine the same to the essential parts. There is illustrated a portion of the frame 1 of a typewriter, and 55 a portion of the rack bar 2 which is attached to the carriage (not shown), and which meshes with a pinion or spur gear 3 secured upon a rotatable shaft 4 journaled in suitable bearings 5 of the frame 1. The character 60 keys are designated by the reference character 6, and the shift keys by the numeral 7, while the spacing key is designated 8. The keys 6 are carried by the key levers 9, as is also the spacing key 8, and the case shift 65 keys 7 are carried by the shift levers or

members 10. The foregoing parts are common in present day typewriters, and are to be taken as typical only, since the present mechanism can be used with various styles and constructions of typewriters.

The gist of the invention resides in the provision of an especially constructed escapement wheel, and elements coöperating therewith. The escapement wheel is designated generally by the numeral 11, and is 70 mounted loosely upon the shaft 4, preferably between the bearings 5. This escapement wheel 11 is rotated or actuated by the carriage as the carriage is moved during the printing operation, and when the carriage 75 is returned to starting or initial position, the escapement wheel 11 remains stationary. This is carried out by means of a ratchet wheel 12 secured upon the shaft 4 at one side of the escapement wheel 11 and engaged 80 by a pawl or dog 13 carried by said side of the escapement wheel, while a second ratchet wheel 14 is secured to the opposite side of the escapement wheel 11 and is engaged by a pawl or dog 15 carried by the frame. 85 Thus, when the carriage is advanced so that the rack bar 2 is advanced, the shaft 4 being rotated due to the rotation of the pinion 3 by the rack bar 2, will rotate the ratchet wheel 12, and said ratchet wheel 90 being engaged by the pawl 13 carried by the escapement wheel 11, will cause the escapement wheel to rotate, but when the carriage is returned, the ratchet wheel 12 can 95 turn idly without rotating the escapement 100 wheel 11 in a retrograde direction, since the teeth of the ratchet wheel 12 simply move past the pawl 13. The reverse rotation of the escapement wheel 11 is prevented by the pawl 15 in engaging the ratchet wheel 14 105 attached to the escapement wheel, and this holds the escapement wheel in proper position.

The escapement wheel 11 is provided with an annular series of bores or apertures 16 110 extending from one side to the other parallel with the axis of the shaft 4, although said apertures can be arranged otherwise. These apertures are preferably arranged adjacent the periphery or margin of the wheel 11 and a pin 17 is slidable with each aperture 16 transversely of the wheel, or from one side of the wheel to the other. The wheel 11 is provided with bores or recesses 18 extending radially, and extending from 115 the periphery of the wheel so as to intersect the respective apertures 16. Disposed within each bore 18 is a ball or holding element 19 at the inner side of the respective pin 17, and a coiled wire expansion spring 20 is 120 seated within the bore 18 behind the ball 19 to move into engagement with the pin 17. Each pin 17 has a pair of annular grooves 125 or recesses 21 into which the ball 19 is movable, the ball moving into one groove when 130

the pin is in one position, and moving into the other groove when the pin is in its opposite position. The balls 19 have three functions, namely, they prevent the pins 17 from leaving the escapement wheel 11 accidentally, they hold the pins in either position, and they also assist in moving the pins into either position since the balls in being forced into the grooves 21 by the springs 20 will thereby tend to move the pins to one position or the other, when the ridges between the pins are moved past the balls.

Coöperating with the pins or teeth 17 of the ratchet wheel 11 is an oscillatory pallet member or arm 22 mounted for oscillatory movement upon a shaft 23 which is slidable in bearings 24 and 25 of the frame 1, the arm 22 being preferably disposed between said bearings. The upper free end of the arm 22 has opposite pallets 26 and 27 straddling the peripheral or marginal portion of the wheel 11 and movable alternately into the paths of the opposite ends of the pins 17. This pallet arm 22 stops or limits the rotation of the escapement wheel 11, and is normally in the position illustrated in Fig. 3, whereby the rear ends of the pins 17 coöperate with the pallet 27 to prevent the rotation of the escapement wheel 11 unless provided for by the depression of a key. The pins 17 normally project rearwardly or to the rear side of the wheel 11, as seen in Figs. 2 and 3, so that they do not project from the forward side or face of the wheel.

In order to move the pins 17 to normal rearward position as they leave the pallet arm 22, a curved cam or tongue 28 is carried by the frame 1 in rear of the arm 22, and is arranged to force any pins rearwardly which project from the forward side of the wheel as the wheel rotates. Thus, all of the pins 17 are moved rearwardly before they again reach the pallets.

Some means must be provided for moving the pins 17 forwardly for coöperation with the pallet 26, at different distances therefrom, and as one of several means for accomplishing this result, there are employed three oscillatory arms 29, 29' and 29" mounted upon the shaft 23, there being three of said arms to provide three different spaces for small, medium and wide characters, although various numbers of arms or members for this purpose can be used. The arms 29, 29' and 29" are mounted upon the shaft 23 between the bearings 25 and another bearing 30 in which said shaft is slidable, and a guide or slide 31 is provided with brackets 32 engaging the shaft 23 and holding the arms 29, 29' and 29" therebetween, whereby when said slide 31 is shifted, the arms are moved therewith approximately longitudinally of the periphery of the escapement wheel 11. The brackets 32 can be se-

cured to the shaft 23 so that said shaft will slide with the slide 31 and arms 29, 29' and 29", the arm 22 being held in position by the bearings 24 and 25. This shifting of the arms 29, 29' and 29" is utilized for changing the spacing for small and capital letters and other characters. In order to support the slide 31 for reciprocatory movement in connection with the shaft 23, the slide 31 has a tongue 33 movable in a slot 34 of the frame 1. Pivoted to the upper free end of each of the arms 29, 29' and 29" is an angularly extending finger 35, said fingers having stops 36 to normally contact with the arms for holding said fingers at an obtuse angle with the arms. The free ends of the fingers 35 project in rear of three pins 17, which are predetermined distances from the pallet arm 22, and the fingers 35 are swung yieldably to normal position by suitable springs 37, and the arms 29, 29' and 29" are normally swung rearwardly to idle position by springs 38 connecting said arms and slide 31, whereby the fingers 35 are moved rearwardly away from the pins 17 so as not to interfere therewith.

Suitable means are employed for operating the arms 29, 29' and 29" selectively when the character keys are depressed, and as one way of accomplishing this result, the free ends of the arms 29, 29' and 29" are provided with extensions 39 which normally rest upon the upper ends of lift bars 40, 40' and 40", respectively, slidable vertically through the slide or guide 31. The lower ends of the bars 40, 40' and 40" are bifurcated or notched, as at 41, to straddle or otherwise engage the rear cross pieces of the respective levers or rockers 42, 42' and 42". Said levers are of rectangular form, one being disposed within the other, and are mounted for oscillation upon a transverse shaft 43. Springs 44 normally pull the bars 40, 40' and 40" downwardly to normal position, thereby also restoring the levers 42, 42' and 42" to initial position when they are free to do so. Links 45 connect the forward cross pieces of the levers 42, 42' and 42" with the key levers 9, said links being preferably provided with hooks or loops in which said key levers are seated, and the links connecting the proper key levers and levers 42, 42' and 42", whereby when the small characters, such as the letters i, j, and the like, and the period, comma, colon, etc., are typewritten, the respective key levers in being depressed will swing the lever 42. The normal sized letters or characters have their key levers connected to the lever 42', while the wide letters have their key levers connected to the outer lever 42". The levers of the spacing key 8 can be connected to any one of the levers 42, 42' or 42", whichever is desired, and a plu-

rality of spacing keys can be provided for operating the various levers 42, 42' and 42'' to provide various blank spaces. When the levers 42, 42' and 42'' are operated, they 5 lift the lift bars 40, 40' and 40'' so that the extensions 39 are raised, and swung toward the escapement wheel 11, the arms 29, 29', and 29'' being swung with said extensions thereof, it being understood that only one 10 of said arms is swung at one time. The bars are slideable in lines arranged chordally relative to a circle having the shaft 23 as a center, so that the free end or extension 39 in being moved by the respective end 15 of a lift bar will rotate the arm through a certain arc, and the bar can then move farther without moving the arm. This provides for the operation of the escapement before the character key is completely de- 20 pressed, in order that the escapement can have sufficient opportunity to operate before the type strikes the platen.

The pallet arm 22 is operated when either of the levers 42, 42' or 42'' are operated, 25 and as a simple means for accomplishing this result, the arm 22 has an auxiliary arm 46 to which is connected a rod 47 having its other end attached to a transverse rod 48 seating upon the rear arms of the levers 42, 42' and 42'' and held in place by upstanding lugs 49 carried by said arms of said levers, whereby when any one of said levers is operated, it will lift the rod 48 and its rod or stem 47 to raise the arm 46, and swing 35 the arm 22 rearwardly, thus removing the pallet 27 from the pin 17 which rests against it, and bringing the pallet 26 adjacent the wheel 11 to lie in the path of the pin 17 which is moved forwardly by either of the 40 arms 29, 29' or 29''. The rod 48 is normally moved downwardly by means of springs 49a, to return the arm 22 to normal position when the character key is released.

Means are provided whereby when either 45 of the shift key levers are depressed, the slide 31 is shifted for varying the spacing movement of the escapement wheel or member 11, whereby capital letters and other large characters will be given wider spaces 50 than the small letters and other characters. Thus, longitudinal rock shafts 50 at the opposite sides are journaled in suitable bearings 51 of the frame 1, and have attached thereto arms 52 connected by links 53 with 55 the shift key levers 10, said links 53 having hooks at their lower ends in which the levers 10 are seated. Thus when either lever 10 is depressed, the other lever need not be, which is the same case with the levers 9, 60 since when any lever 9 is depressed, the others remain in place. The rock shafts 50 have second arms 54 attached thereto, which are connected by links 55 with the ends of the slide 31. The arms 52 and 54 in connection with the rock shafts 50 provide bell

crank levers, whereby when either of the levers 10 is depressed, it will result in the slide 31 being shifted from the bearing 25 to the bearing 30, thus moving the arms 29, 29' and 29'' and their lift bars one pin farther away from the pallet arm 22.

The operation of the mechanism is as follows:

The carriage, which is ordinarily under tension so as to be advanced when free to do so, transmits its motion by means of the rack bar 2 and pinion 3 to the shaft 4 and ratchet wheel 12 carried thereby. The pawl 13 carried by the escapement wheel 11 in engaging the ratchet wheel 12, will prevent the movement of the rack bar 2 as long as the escapement wheel cannot be moved, and said wheel cannot move due to the fact that one of the rearwardly projecting pins 17 rests against the pallet 27. The pins in advance of the pallet 26 are all pushed back, this being accomplished by the cam 28 which pushes the pins back to normal position as they leave the pallet 26. Now, supposing the key of the small letter i, the period, comma, or the like, is depressed, it will pull down on the respective link 45 which is connected to the forward arm or cross piece of the lever 42, swinging the forward arm of said lever downwardly, and swinging the rear arm thereof upwardly. The lift bar 40 is therefore raised, which will swing the arm 29 forwardly so that its finger 35 pushes the pin 17 which is in front of it forwardly to project from the forward side of the escapement wheel 11, and at the same time that the lever 42 is swung, the rod 48 is raised, as is also the stem 47, thus swinging the arm 46 upwardly. When the arm 46 is swung upwardly, the arm 23 is swung rearwardly, thereby removing the pallet 27 from its pin 17 at the same time that the other pin 17 is pushed forwardly by the arm 29, and this releases the escapement wheel, letting it rotate a short step, until the pin 17 which was pushed forward by the arm 29 strikes the pallet 26, said pallet 26 being brought adjacent the wheel 11. Thus, the wheel 11 can rotate a short step, to let the rack bar 2 and carriage move a short step when the small letter i, period, comma, or similar character is printed. Attention is directed to the fact that when the lift bar 40 or either of the other lift bars is raised, the respective pin 17 is pushed forwardly before the character key is depressed, due to the fact that the extension 39 is swung to final position before the lift bar is completely elevated, the remainder of the upward movement of the lift bar being an idle one. The pin 17 is therefore projected forwardly and the pallet 27 is moved to releasing position, before the character key is completely depressed, thus assuring the operation of the escapement before the im-

print is made, and thereby eliminating blurring. When the key is released so as to rise to normal position, the arm 29 swings rearwardly after the lift bar 40 is moved downwardly by its spring 44, and the lever 42 is also being returned to normal position which allows the rod 48 and its stem 47 to move downwardly, so that the pallet 26 is removed from the forwardly projecting pin 17 allowing said pin to move past said pallet, but the opposite pallet 27 will simultaneously be moved into operative position to be contacted with by the following pin 17, thus allowing the wheel to turn a partial step. Thus, the escapement wheel can turn a partial step during the return movement of the character key and other parts, and this reduces the amount of movement that the escapement wheel must make when the succeeding character key is depressed. When the character key is depressed that operates the lever 42', the lift bar 40' is raised, thereby operating the second arm 29' which projects a pin 17 forwardly which is slightly farther remote from the pallet 26, in order that the escapement wheel 11 can rotate proportionately farther, for providing a wider space. When the key of a wide character is depressed, the lever 42'' is operated to lift the bar 40'', and swings the arm 29'', whereby a pin 17 still farther remote from the pallet 26 is operated. Thus, the arms 29, 29' and 29'' are operated selectively by the keys, and they project such pins 17 as are predetermined distances from the pallet 26, in order that when the pallet arm 22 is swung simultaneously with either of the arms 29, 29' or 29'', the escapement wheel can rotate a distance proportional to the width of the character being printed.

When either of the shift key levers 10 is depressed, it swings the respective bell crank lever, to shift the slide or guide 31 one pin to the left, as seen in Fig. 1, although the amount that the slide 31 is shifted can be varied. The arms 29, 29' and 29'' are now one pin farther remote from the arm 22, whereby said arms 29, 29' and 29'' are operated, the escapement wheel can rotate a little farther in each case, than when the arms are in the position illustrated in Fig. 1. Consequently, when the shift lever or shifter is operated to change from small to capital letters, the pin operating arms 29, 29' and 29'' are shifted farther from the pallet arm 22, and consequently the pins 17 which are projected forwardly by said arms will be farther remote from the pallet arm than when small letters are printed. Naturally, the capital letters and larger characters will be allotted wider spaces than the small letters and characters, and spaces in proportions to their widths. The shift key lever can be locked in position, whereby a plurality of capital letters or large characters can be made in succession, and as soon as the shift lever is released, the slide 31 will return to normal position, whereby the arms 29, 29' and 29'' are again returned to "small letter" position.

The fingers 35 are mounted to swing away from the pins 17, whereby when one of said fingers 35 has pushed a pin 17 forwardly, the succeeding pins 17 can pass said finger 35 without difficulty, and said finger 35 cannot prevent the advance movement of the escapement wheel. The fingers 35 are normally out of the way of the pins 17, however, so that only that finger 35 which has pushed a pin 17 forwardly need swing out of the way of the following pin or pins.

The circle in which the pins 17 are arranged can be sufficiently larger in diameter than the pinion 3, whereby a proportionately greater movement of the pins 17 is provided, so that a more minute spacing movement of the carriage is accomplished.

Another cardinal advantage of the present mechanism resides in the fact that the carriage can be returned and stopped at any point desired, whereby a line may be started at any desired point, or whereby a character can be placed at any selected point on the line. This renders the invention useful in connection with billing and similar typewriters, since the characters can be readily placed in different columns, and column stops such as are ordinarily used can be made adjustable for stopping the carriage at many more points than is now possible with the uniform spacing movement of the carriage. It is evident that when the carriage is returned, the rack bar 2 in being returned will rotate the pinion 3, shaft 4 and ratchet wheel 12, the teeth of the ratchet wheel 12 moving past the pawl 13, whereby when the carriage is stopped at any point within very small fractions of an inch, one tooth of the ratchet wheel will always be in a position to engage the pawl 13 to hold the carriage in such position, the escapement wheel 11 remaining in its last position during the return movement of the carriage, so that as soon as the carriage is again in position to feed forwardly, the escapement mechanism is in position to perform its duty.

In Fig. 6, there is illustrated a specimen of the work done by an ordinary typewriter, it being noted that the spaces S of the various characters are uniform or of the same width, and that some of the characters are allotted spaces narrower than they should occupy, that other characters occupy spaces wider than they should, and that other characters are made wider in proportion to fill up the spaces. This method involves the use of characters of uniform width. Now, by referring to Fig. 7 wherein a specimen of the work of a typewriter employing the present escapement mechanism, is depicted, it

will be noted that the spaces allotted the various characters are in proportion to the relative widths of the characters. Thus, the small letter i, the periods, the commas, etc., 5 occupy narrow spaces S^1 and the medium small characters occupy medium spaces S^2 , while the wide small characters occupy wide spaces S^3 . Turning to the capital letters or 10 large characters, it will be noted that the letter I occupies a wider space than that occupied by the small letter i, as indicated at S^4 , the same also being true of the letter J. The medium large characters occupy spaces 15 S^5 of greater width than the spaces occupied by the corresponding small characters, and the wide large characters occupy spaces S^6 larger in width than the spaces occupied by the corresponding small characters. In this manner, the various characters are printed 20 in spaces proportional to their widths, in order that a neat and pleasing effect is provided, and the use of printers' type made possible.

Having thus described the invention, what 25 is claimed as new is:

1. An escapement mechanism embodying a pallet device, an escapement means having a series of means normally in one position and movable to another position to coöperate with the pallet device, means for moving said second mentioned means individually and selectively to second mentioned position at different distances ahead of the pallet device and operable to move only one of 30 said second mentioned means at a time, the pallet device having means movable to coöperate with that one of the second mentioned means that is moved to second mentioned position to control the steps made and 35 having means to stop the escapement means when the first mentioned means of the pallet device is moved to releasing position.

2. An escapement mechanism embodying a pallet device, an escapement means having a series of means normally in one position and movable to another position to coöperate with the pallet device, a plurality of key-operated devices for moving the second mentioned means selectively to second 45 mentioned position at different distances ahead of the pallet device, said pallet device being operated whenever one of said plurality of devices is operated, the pallet device having a pallet movable to coöperate 50 with one of the second mentioned means when in second mentioned position and an alternately movable pallet to stop the escapement means when the first mentioned pallet is moved to releasing position.

60 3. An escapement mechanism embodying a pallet device, an escapement member having teeth normally in one position and movable to another position, means for moving the teeth individually and selectively to second 65 mentioned position at different distances

ahead of the pallet device and operable to move only one of said teeth at a time, the pallet device having means coöperable with that tooth that is moved to second mentioned position to control the steps made and having means to stop the escapement member when the first mentioned means of the pallet device is moved to releasing position. 70

4. An escapement mechanism embodying a pallet device, an escapement member, a series of teeth carried by said member normally in one position and movable to another position to coöperate with the pallet device, a plurality of key-operated devices for moving said teeth selectively to second mentioned position at different distances ahead of the pallet device, the pallet device having a pallet movable into the path of the teeth when in second mentioned position and an alternately movable pallet to stop the escapement member when the first mentioned pallet is moved to releasing position, the pallet device being operated whenever one of 80 said plurality of devices is operated. 85

5. An escapement mechanism embodying a pallet device, an escapement wheel having an annular series of teeth normally in one position and movable to another position, means for moving said teeth individually and selectively to second mentioned position 90 at different distances ahead of the pallet device and operable to move only one of said teeth at a time, said device having means movable into the path of that tooth that is moved to second mentioned position to control the steps made and having means to stop the escapement wheel when the first mentioned means of the pallet device is moved to releasing position. 95

6. An escapement mechanism embodying a pallet device, an escapement wheel, an annular series of teeth carried by the wheel normally in one position and movable to another position, a plurality of key-operated devices for moving said teeth selectively to second mentioned position at different distances ahead of said pallet device, the pallet device being operated when any one of said plurality of devices is operated, the pallet device having a pallet movable into the path of the teeth when in second mentioned position and an alternately movable pallet to stop the escapement wheel when the first mentioned pallet is moved to releasing position, and means for returning the teeth to normal position after they have passed the first mentioned pallet. 100 110 115 120

7. An escapement mechanism embodying an escapement means having a series of means normally in one position and movable to another position, means operable for individually and selectively moving the second mentioned means to second mentioned position one at a time only, and a pallet device engageable with that one of said second 125 130

mentioned means that is moved to second mentioned position to control the step made by the escapement means and stopping the escapement means when said second named 5 means is released.

8. An escapement mechanism embodying a pallet device, an escapement member having a series of teeth normally in one position and movable to another position, and 10 means for moving the teeth individually and selectively from normal to second position one at a time only at different distances ahead of the pallet device, said pallet device being coöperable with that tooth that is 15 moved to second position to control the step made by the escapement member and stopping the escapement member when said tooth is released.

9. An escapement mechanism embodying 20 a pallet device, an escapement wheel, an annular series of teeth carried thereby normally in one position and movable to another position, and a plurality of key-operated devices operable individually and coöperable with said teeth at different distances 25 ahead of the pallet device for moving one of said teeth at a time only from normal to second position, said pallet device being coöperable with said tooth when in second position for controlling the step made by said wheel and stopping the wheel when said tooth is released.

10. An escapement mechanism embodying 35 a pallet device, an escapement member having a series of teeth normally in one position and movable to another position, means for moving said teeth individually and selectively to second mentioned position at different distances ahead of the pallet device, 40 said means being operable to push a single tooth only to second mentioned position for coöperation with the pallet device, the pallet device being operated when said means is operated and having a pallet to move in 45 front of a tooth when in second mentioned position to control the step made, the pallet device having means for stopping the escapement member when said pallet is removed from said tooth.

50 11. An escapement mechanism embodying a pallet device, an escapement member having a series of movable teeth normally in one position and movable to another position to coöperate with said device, and 55 means for moving said teeth from normal to second mentioned position including a movable member and a movable portion carried by said member to engage the teeth and adapted to be moved out of the way there- 60 of by the teeth following that one moved to second mentioned position.

12. An escapement mechanism embodying 65 a pallet device, an escapement member, a series of movable teeth carried thereby nor- mally in one position and movable to an-

other position to coöperate with said device, and means for moving said teeth to second mentioned position ahead of the pallet device, and including a swinging member and a spring pressed portion pivoted to said 70 member and adapted to contact with one tooth to push it to second mentioned position, said portion being adapted to be swung out of the way by those teeth following the one pushed to second mentioned position. 75

13. An escapement mechanism embodying in combination with a depressible key, an escapement device, a movable member controlling said device, and a second movable member operated when the key is depressed, 80 the first mentioned member having a portion bearing against the second mentioned member to be moved thereby, the second mentioned member being movable past said portion after the first mentioned member has 85 been moved.

14. An escapement mechanism embodying in combination with a depressible key, an escapement device, an oscillatory arm for controlling said device and having a terminal, and a reciprocatory bar operated when said key is depressed, said terminal resting against one end of said bar to be moved thereby, said bar being movable past said terminal during the completion of the de- 90 pression of said key. 95

15. An escapement mechanism embodying an escapement wheel having an annular series of apertures and bores intersecting said apertures, pins slidable in said apertures to project from one side or the other of said wheel, said pins each having a pair of grooves, balls in said bores engageable in said grooves, and springs seated in said bores for pressing the balls into said grooves. 100 105

16. An escapement mechanism embodying a pallet device, an escapement means coöperable therewith and operable at different distances therefrom for varying the steps made by said means, means for selectively operating the escapement means for coöperation with the pallet device, and means operable to change the operation of the second mentioned means relative to the pallet device to change the steps made by the es- 110 capement means. 115

17. An escapement mechanism embodying a pallet device, escapement means having a series of means normally in one position and movable to another position to coöperate 120 with the pallet device, and means for individually and selectively moving the second mentioned means to second mentioned position at different distances from the pallet device to coöperate therewith and to control the steps made by the escapement means, the pallet device being operated when the third mentioned means is operated and being coöperable in one position with the es- 125 capement means to stop it and in another 130

- position with the second mentioned means when in second mentioned position to control the steps made.
18. An escapement mechanism embodying a pallet device, an escapement member having a series of movable teeth normally in one position and movable to another position, and a plurality of key-operated devices for individually and selectively moving said 10 teeth to second mentioned position at different distances ahead of the pallet device to coöperate with said device, the pallet device being operated when any one of said plurality of devices is operated, and the pallet 15 device being operable in one position to stop the escapement member and being operable in another position to engage that tooth that is moved to second mentioned position to control the step made.
19. A mechanism embodying stopping means, means movable past said stopping means and having a series of means to coöperate therewith, actuating means for operating said series of means at different 25 distances from the stopping means to coöperate therewith and determine the movement of the movable means, and means operable for changing the relative distances of operation from the stopping means of said series of means by the actuating means.
20. A mechanism embodying stopping means, a member movable past said means and having a series of movable teeth, actuating means for moving said teeth at different 35 distances from the stopping means to contact therewith and determine the amount of movement of said member, and means operable for changing the relative distances that said teeth are moved from the stopping 40 means by the actuating means.
21. A mechanism of the character described embodying an escapement wheel, operating means, a pallet device operated by said means coöperable with said wheel, movable teeth carried by said wheel and engageable with said device for varying the steps made, means operated by the operating means for moving said teeth for coöperation with the pallet device, and means for changing the relative operation of said teeth by the operating means.
22. A mechanism of the character described embodying an escapement wheel having movable teeth, a pallet device coöperable 55 with said teeth for varying the steps made, a plurality of devices for moving said teeth for coöperation with the pallet device, and means for changing the relative operation of said teeth by said devices.
23. A mechanism of the character described embodying key members, an escapement wheel having movable teeth, a pallet device coöperable with said teeth for varying the steps made, a shift controlling member, 65 means operated by the key members for mov-
- ing said teeth for coöperation with the pallet device, and means controlled by the shift controlling member for changing the relative operation of said teeth by the last mentioned means.
24. A mechanism of the character described embodying key members, a shift controlling member, a ratchet wheel having movable teeth, a pallet device coöperable with said teeth for varying the steps made, 70 a plurality of devices operated by the key members for moving said teeth for coöperation with the pallet device, and means operated by the shift controlling member for changing the operative relation between said teeth and devices.
25. A mechanism of the character described embodying an escapement wheel having movable teeth, a pallet device, means for moving the teeth for coöperation with the pallet device, said means and pallet device being relatively movable, and means for moving them relatively, for changing the steps made when they are moved relatively.
26. A mechanism of the character described embodying an escapement wheel having movable teeth, a pallet device coöperable with said teeth for varying the steps made, and means for moving said teeth for coöperation with the pallet device and movable to and from the pallet device for further changing the steps made.
27. A mechanism of the character described embodying an escapement wheel having movable teeth, a pallet device coöperable with said teeth for varying the steps made, means for moving said teeth for coöperation with said device to vary the steps made, and means for changing the operative relation between the last mentioned means and pallet device.
28. A mechanism of the character described embodying key members, an escapement wheel having teeth normally in one position and movable to another position, a pallet device engageable with said teeth when in their second mentioned position, and a plurality of devices operated by the respective key members, one at a time, for moving a single tooth from its normal to its other position ahead of the pallet device.
29. An escapement mechanism embodying in combination with character keys and a case shift device, a pallet device, escapement means coöperable with said pallet device and operable at different distances from said pallet device for varying the steps made by said means, and means controlled by said keys and coöperating with the aforesaid means to operate the same for coöperation with the pallet device, the last mentioned means and pallet device being operated at different relative positions when the shift device is operated.
30. An escapement mechanism embodying

- in combination with character keys and case shift device, a pallet device, escapement means having means operable at different distances from said escapement means, a plurality of devices for operating said second mentioned means at different distances from the pallet device and operated selectively by the keys, said plurality of devices being operable at different positions relative to the pallet device, when the shift device is operated. 10
31. An escapement mechanism embodying in combination with character keys and a case shift device, an escapement member, a pallet device, a series of teeth carried by said escapement member and coöperable with said pallet device for varying the steps made by said member, said teeth being movable to different positions, and means controlled by the shift device and controlled by the keys for moving said teeth from one position to another at different distances relative to the pallet device. 15
32. An escapement mechanism embodying in combination with character keys and a case shift device, an escapement member, a pallet device, teeth movably carried by said member and movable from one position to another to coöperate with said pallet device for varying the steps made by said member; a plurality of devices controlled selectively by the keys and operable for moving said teeth from one position to another in advance of said pallet device, and means operated by the shift device for rendering said plurality 30 of devices operable at different distances relative to the pallet device.
33. An escapement mechanism embodying an escapement member, a pallet device, series of movable teeth carried by said member and movable to different positions to coöperate with said device for varying the steps made by said member, means for moving said teeth from one position to another at different distances from said pallet device, and means operable to change the relative distances that the aforesaid means is operable from the pallet device. 40
34. An escapement mechanism embodying an escapement wheel, a pallet device, an annular series of teeth carried by said wheel for movement from one position to another and coöperable with said device for varying the steps made by said wheel, a plurality of devices coöperable with said teeth for moving them from one position to another in advance of said pallet device, and means operable to change the distances that said plurality of devices are operable from the pallet device. 50
35. An escapement mechanism embodying in combination with character keys and a case shift device, an escapement member, a pallet device, a series of teeth carried by said member and movable to different positions to coöperate with the pallet device, when the shift device is operated. 55
- for varying the steps made by said member, a slide, means movable with said slide and operated by said keys for moving said teeth from one position to another ahead of the pallet device, the pallet device being operated when said means is operated, and said shift device being connected to said slide to move the same from one position to another relative to the escapement member and pallet device. 70
36. An escapement mechanism embodying in combination with character keys and a case shift device, an escapement member, a series of teeth carried thereby and movable to different positions, a pallet device coöperable with said teeth, a slide, a plurality of devices operated selectively by the various keys and operable for moving said teeth at different distances in front of said pallet device, the shift device being operatively connected to said slide to move the same to different distances from the pallet device, said plurality of devices being movable with the slide. 75
37. An escapement mechanism embodying in combination with character keys, and a case shift device, an escapement wheel, an annular series of teeth carried thereby normally at one side thereof and movable to the opposite side, a pallet device having a pallet to stop the movement of the wheel and having a second pallet coöperable with said teeth when in one position, the pallets being operated simultaneously and alternately, a slide, means moved with the slide 100 and operated by said keys for moving said teeth from normal to second position ahead of the second pallet, the pallet device being operated when said means is operated, said slide being moved to different positions by the shift device, and means for returning said teeth to normal position after they pass the second pallet. 105
38. An escapement mechanism embodying in combination with character keys and a case shift device, an escapement wheel, an annular series of teeth carried thereby and normally at one side of said wheel and movable to the opposite side, a pallet device having a pallet to stop the wheel and having a second pallet coöperable with said teeth when moved to their second position, means for returning said elements to normal position after they have passed the second pallet, a plurality of devices movable with said slide and operated selectively by the keys, said plurality of devices being operable for moving said teeth from their normal to their second position at different distances ahead of the second pallet, said slide being operated by the shift device to move said plurality of devices to different distances from the pallet device, the pallet device and both of its pallets being operated when any one of the said plurality of devices is operated. 110

- 125
- 130

39. A mechanism having stopping means, means movable past said stopping means and having a series of means coöperable with said stopping means, a plurality of 5 actuating means for operating said series of means at different distances from the stopping means to coöperate therewith and determine the movement of the movable means, and means operable for changing the operation of said series of means by the actuating means.

40. A mechanism embodying stopping means, a member movable past said means and having a series of movable teeth, a plu-

rality of actuating devices for moving said 15 teeth at different distances from the stopping means to coöperate therewith and determine the amount of movement of said member, and means operable for changing the movement of said teeth by said devices. 20

In testimony that I claim the foregoing as my own, I have hereto affixed my signature in the presence of two witnesses.

MONROE E. MILLER.
